ABRAHAM NOVICK, OF FLUSHING, NEW YORK, ASSIGNOR TO F. L. SMITH MACHINE CO., INC., OF NEW YORK, N. Y., A CORPORATION OF NEW YORK

BLANK HOLDER

Application filed December 19, 1927. Serial No. 241,001.

This invention relates to blank holders, and has for its object to provide simple and efficient means for holding a multiplicity of blanks in orderly, stacked form for handling and shipping.

It is an object of the invention to provide a stack holder which can be made at small expense, and which will function efficiently, with assurance that no disarrangement of the blanks will be permitted.

It is a further object of the invention to provide means for retaining the blank stack in assembled relation with the holder, which means can be conveniently applied to the holder and can also be readily detached therefrom when it is desired to release the blanks for use.

Other objects and advantages will herein-after appear.

26 In the drawings forming a part of this specification:

Figure 1 is an elevation showing a stack of blanks held together by holding means embodying the present invention;

25 Figure 2 is a transverse, sectional view taken on the line 2—2 of Figure 1, looking in the direction of the arrows;

Figure 3 is a bottom, plan view of the assembly shown in Figure 1; and

30 Figure 4 is an enlarged, bottom plan view showing the relation of the holding and locking members.

For purposes of illustration, disclosure is made in the drawings of a stack of fastener blanks 1 of a type employed for detachably fastening the seal flap of an envelope down to the body thereof. These blanks at the stage shown in the drawings are flat and are provided with body members 2 and 3 and with ends arms 4 and 5. The blanks are designed to be introduced into the magazine of a machine of a kind well known in the art, in which machine prongs are formed in the body members 2 and 3 and these prongs are clinched to the back of the envelope ready for use. By folding the arms 4 and 5 of an attached fastener upward into substantial parallelism, passing them through a hold in the envelope flap, and then folding them down, the flap may be held closed but with

capability for being released by again bending the arms 4 and 5 into parallelism.

The blanks are formed of thin metal, and as is evident from an inspection of the drawings, are cross shaped so that opposed re-entrant angles occur at the junctions of the body portions 2 and 3 with the arms 4 and 5.

For the purpose of maintaining a multiplicity of these blanks in orderly assembled relation for shipment to envelope factories and for handling in such factories, provision

is made of a staple-like member 6 having parallel legs 7 and 8 thereof disposed in opposite re-entrant angles of the blank stack so as to embrace and interfit with the blanks. This staple-like holding member 6 may be of considerable length, and the legs, although resilient and not, therefore, permanently distortable, are bendable to a limited extent.

The legs 7 and 8 extend beyond the stack as shown, and provision is made of a holding plate 9 and a locking plate 10, both of which are impaled upon the projecting portions of such legs to maintain the stack against separation from or disarrangement relative to the holding member 6.

The holding plate 9 has impaling holes formed therein which may be spaced apart approximately the same distance as the normal spacing of the staple legs 7 and 8. The locking plate 10 is desirably originally of identically the same construction as the holding plate 9, although it has been shown as of slightly smaller dimensions in the drawings for clearness of illustration.

For the purpose of diminishing the distance between the impaling holes of the locking plate 10 it is permanently distorted by bending between its ends so that the spacing between the impaling holes is somewhat less than the normal spacing of the legs 7 and 8 of the staple-like holding member 6. With this construction the impaling of the holding plate 9 upon the staple legs does not produce any distortion thereof, but tends to maintain the stack engaging lengths of said legs in

parallelism so that disarrangement of the stack is guarded against. The impaling of the locking plate 10 upon the legs 7 and 8, however, tends to change the distance between the projecting ends of the legs, and thereby

puts the legs under stress. As the plate 10 is forced toward the plate 9, the stress increases so that the outer sides of the legs 7 and 8 become frictionally bound against the impaling holes in locking plate 10, and the inner sides of the legs 7 and 8 are forced into frictional binding engagement with the impaling holes in holding plate 9.

With the arrangement described, there is no danger of accidental misplacement of the holding plate 9, and hence no danger of disarrangement of the stack. When it is desired to release the stack from the holding member, however, it is a simple matter to withdraw first the locking plate 10 and then the holding plate 9 from the legs of the holding member 6.

While I have illustrated and described in detail certain preferred forms of my invention, it is to be understood that changes may be made therein and the invention embodied in other structures. I do not, therefore desire to limit myself to the specific constructions illustrated, but intend to cover my invention broadly in whatever form its principle may be utilized.

I claim:

1. A stack holder for a multiplicity of blanks, comprising an open-mouthed staple-like member having the legs thereof interfitting with the blanks, a holding member removably impaled on the legs of the staple-like member, and a locking member also removably impaled on the legs of the staple-like member in frictional binding relation thereto.

2. A stack holder for a multiplicity of blanks, comprising a staple-like member having bendable legs interfitting with the blanks and projecting therebeyond and terminating in an open mouth, a holding member removably impaled on the projecting legs of the staple-like member, the leg receiving holes thereof being spaced approximately the same as the legs, and a locking member also removably impaled on the legs of the staple-like member, the leg receiving holes of the locking member being spaced differently from the holes of the holding member, whereby the holding and locking members cooperate to stress the legs and cause them to be bound frictionally to the holding and locking members.

3. A stack holder for a multiplicity of blanks, comprising a staple-like member having bendable legs interfitting with the blanks and terminating in an open mouth, and a holding member impaled on the legs of the staple-like member and adapted to stress and frictionally bind upon said legs.

4. A holder for a stack of shim-like blanks, each blank having opposite re-entrant angles formed therein, said holder comprising a staple-like member embracing the stack and having the legs thereof engaging in the re-

entrant angles of the blanks and projecting beyond the stack and terminating in an open mouth, and holding means secured frictionally to the projecting portions of said legs and packing the blanks snugly in said holder.

In testimony whereof I have affixed my signature to this specification.

ABRAHAM NOVICK.
